POWER TRANSMITTER FOR POWER TABLES

Irving F. Webb, Elizabeth, N. J., assignor to The Singer Manufacturing Company, Elizabeth, N. J., a corporation of New Jersey

Application August 21, 1933, Serial No. 685,996

8 Claims. (Cl. 192—17)

This invention relates to improvements in power-transmitters for sewing and like machines, and more particularly in power-transmitters of the type disclosed, for instance, in the United States Patent No. 468,357, Feb. 9, 1892, to F. Müller, according to which power may be transmitted at will from a constantly-running driving pulley to a pulley of the driven machine.

The invention has for an object to provide simple means for quickly and accurately applying a power-transmitter to a power table, with the axis of rotation of the driving and driven elements of the transmitter in proper position.

A further object of the invention is to provide a power table with a power-transmitter so arranged as to permit of readily changing the table-top to accommodate different varieties of machines.

The invention consists in the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a side elevation of the power-transmitter as applied to a power table shown partly in vertical section. Fig. 2 is a top plan view of the transmitter, with the table and transmitter supporting structure in horizontal section. Fig. 3 is a fragmentary end elevation of the power table as viewed from the right in Fig. 1. Fig. 4 is a detail view in side elevation of the tie-member, the clamp therefor and a portion of the table standard.

Referring to the drawings, the power-transmitter which constitutes an improvement of that disclosed in the aforesaid U. S. Patent No. 468,357, is shown as applied to a power table forming the subject of the U. S. patent to G. M. Eames, No. 1,695,419, Dec. 18, 1928, to which patents reference may be had for an understanding of details of construction which have not been herein disclosed because they are deemed unessential to a full comprehension of the present invention.

The power table has a table-top 1 upon which a sewing or other machine (not shown) is secured, the table-top 1 being suitably cut away to receive the machine or otherwise provided with machine locating and securing means, as is well understood in the art. The table-top 1 is mounted upon a supporting structure including, in the present instance, an inverted U-shaped end rail 2 disposed transversely of and underlying the

table-top 1. Entering the end rail 2 and suitably secured thereto, as by welding, are the upper ends of supporting standards (only one of which is shown in the drawings), each comprising a primary channel-bar leg-member 3 and a supplementary channel-bar leg-member 4 slidably disposed for vertical adjustment within the leg-member 3, said leg-members being substantially U-shaped in horizontal section.

In order to provide for ready replacement of the table-top 1 to thereby adapt the power table for different machines, the power-transmitter is in the present case attached directly to the table-top supporting structure, instead of being secured to the underside of the table-top as in said Patent No. 468,357. The power-transmitter is rigidly secured to the table-top supporting structure in a manner providing for readily setting up the complete power table, as well as for conveniently effecting angular adjustment of the transmitter into proper position.

To this end, the power-transmitting elements are preferably mounted upon an angular hanger comprising a horizontal bracket-member 5, a bracket-member 6 depending vertically from the horizontal member 5, and a channeled bracket-extension 7. Fixedly carried by the vertical bracket-member 6 is the horizontally disposed, tubular stud-shaft 8 upon which are rotatably journaled the driving and driven elements 9 and 10, of which the driving element 9 comprises a stepped pulley having belt connections (not shown) with any suitable power source and the driven element 10 is in the form of a pulley adapted to be connected by a suitable belt (not shown) with a machine upon the table-top 1.

The driving element 9 is shiftable axially of the shaft 8 into frictional driving engagement with the driven element 10 by means of a three-armed lever fulcrumed upon a pivot-bolt 12 spanning the channel of the bracket-extension 7. One arm 13 of said three-armed lever adjustably carries a thrust-plug 14 for engagement with a thrust-receiving disk 15 upon the driving element 9; a second arm 16 of said lever terminates in a claw 17 overhanging the driven element 10 and engageable with a yielding friction material, such as a piece of round leather 18, carried by the bracket-extension 7 and adapted to be pressed as a brake into the groove of the pulley 10. The third arm 19 of said three-armed lever has its free end connected to a suitable treadle or knee-shift, and is also connected by a coiled spring 20 to a bar 21 rigidly projecting from the bracket-extension 7, said spring 20 acting to yieldingly rock the lever 110

13, 16, 19 about its fulcrum-axis 12 to release the driving element from engagement by said lever and to effect braking of the driven element 10. The usual segmental guard 22 is detachably secured by a screw 23 upon the hanger bracket-extension 7, and an oil-well 24 is secured by screws 25 upon the bracket-member 6, said oil well being entered by a wicking 26 depending from the tubular shaft 8 and adapted to carry lubricant to 10 the bearings of the driving and driven elements of the transmitter in substantially the same manner as more fully disclosed in the aforesaid Patent No. 468,357. A belt-guard 27 for the driven element 10 is detachably secured by a screw 28 upon a boss 15 29 at the underside of the oil well 24.

The bracket-member 5 of the hanger has a foot 30, formed with opposed rounded surfaces and provided with apertures 31, loosely entered by bolts 32 extending horizontally through apertures 20 formed in the end rail 2, one of said bolts also passing through the apertures in the upper end of the standard or leg-member 4. By means of nuts 33 threaded upon the bolts 32, the rounded foot is releasably secured against an outer side 25 face of the end rail 2, with the transmitter disposed entirely at one side of the table standard and with the hanger bracket-member 5 close to the under side of the table-top 1. Spacing tubes 34 are preferably provided upon the bolts 32 to 30 reinforce the end rail against distortion when the nuts 33 are tightened, and washers 35 are also preferably interposed between the heads of the bolts 32 and the end rail.

Because of the bolt clearance provided by the 35 apertures 31 of the hanger foot, and the rounded surfaces of said foot, it is obvious that upon slightly releasing the nuts 33, the hanger may be swung angularly to properly position the driving and driven elements of the transmitter with respect to the power source and the machine to be driven. In order to reinforce the described transmitter supporting means and nevertheless provide for conveniently applying the transmitter to a power table, as well as for accurately effecting 40 adjustment of the transmitter, one end of a tie-member 36 is secured by a pivot-bolt 37 upon the depending bracket-member 6 of the hanger. The other end of said tie-member is provided with a horizontally elongated slot 38 entered by a screw 45 39 threaded into an aperture 40 preferably extending entirely through a clamp-block 41. The clamp-block 41 is disposed within the channel of the U-shaped leg-member 4 in a position such that the screw connection of the tie-member 36 50 with the clamp-block is located at the open side of the leg-member channel. Threaded into the clamp-block 41 to extend in a direction transverse to the screw 39 is a clamp-block securing screw 42 which when partially unthreaded in the operative 55 position of the clamp-block engages the inner face of the channeled leg-member 4 and thereby releasably clamps the block 41 to said leg-member.

It is evident from the described securing means 60 for the clamp-block 41 that the latter, together with the screw 42, constitutes an expansion clamp providing for minute adjustment thereof both horizontally and vertically within the leg-member 4, and that accordingly the position of the transmitter may be adjusted by shifting the clamp-block in the leg-member. However, the transmitter may also be adjusted in a fixed position of the clamp-block 41 by endwise adjustment 65 of the tie-member 36 with respect to the clamp-block. In addition to the advantages de-

rived from the described construction in the matter of conveniently and accurately applying the power-transmitter to a power table, it is to be also noted that the expansion clamp arrangement eliminates the objectionable projections at opposite sides of the table standard incidental to the commonly employed expedient of securing the transmitter by screws adjustably engaging opposed outer faces of the table standard.

Having thus set forth the nature of the invention, what I claim herein is:—

1. Supporting means for power-table driving devices, comprising a table-supporting frame, a hanger for said driving devices, means for securing said hanger for angular adjustment upon said frame, a clamp-member, means for releasably securing said clamp-member upon said frame in spaced relation to the hanger securing means, and means adjustably connecting said clamp-member and hanger.

2. Supporting means for power-table driving devices, comprising a table-supporting frame, a hanger for said driving devices provided with a rounded foot, means for releasably securing the hanger foot to said frame to thereby provide for angular adjustment of said hanger, a clamp-member, means for securing said clamp-member for vertical adjustment upon said frame, and a tie-member connecting said clamp-member and hanger.

3. Supporting means for power-table driving devices, comprising a table-supporting frame, a hanger for said driving devices provided with a rounded foot having a bolt aperture, a bolt loosely entering said aperture for releasably securing the rounded foot of said hanger against said frame to thereby provide for angular adjustment of the hanger, a tie-member pivotally connected to said hanger in vertically spaced relation to the hanger foot, and means for adjustably securing said tie-member to said frame.

4. Supporting means for power-table driving devices, comprising a table-supporting frame having a U-shaped channeled standard, a hanger for said driving devices, means for securing said hanger for angular adjustment upon said frame, a clamp-member adapted to be releasably secured within the channel of said standard, and means connecting said clamp-member and hanger for effecting angular adjustment of said hanger.

5. Supporting means for power-table driving devices, comprising a table-supporting frame having a U-shaped channeled standard, a hanger for said driving devices, means for securing said hanger for angular adjustment upon said frame, an expansion clamp adapted to be releasably secured within the channel of said standard, and a hanger-connecting tie-member secured upon said clamp at the open side of said standard channel.

6. Supporting means for power-table driving devices, comprising a table-supporting frame having a U-shaped channeled standard, a hanger for said driving devices, means for securing said hanger for angular adjustment upon said frame, a clamp-block disposed within the channel of said standard, a screw threaded into said clamp-block adapted to engage the inner face of said channeled standard to thereby releasably secure the clamp-block to the standard, a tie-member pivotally connected to said hanger, and means for securing said tie-member to said clamp-block at the open side of the standard channel.

7. Supporting means for power-table driving devices, comprising a table-supporting frame, a

hanger for said driving devices, means for supporting said hanger upon said frame for angular adjustment, a clamp-member secured upon said frame for vertical and horizontal adjustment thereupon, and means connecting said hanger to said clamp-member.

8. Supporting means for power-table driving devices, comprising a table-top supporting structure including an end rail and an end rail standard, a hanger having a substantially horizontally disposed bracket-member and a substantially vertically disposed bracket-member depending

from the horizontally disposed member, said horizontally disposed bracket-member terminating at one end in a rounded foot, means for securing said rounded foot to a side face of said rail for angular adjustment of the hanger, driving devices journaled upon the vertical bracket-member of said hanger, a tie-member pivotally secured upon the vertically disposed bracket-member, and means for securing said tie-member to said end rail standard.
